United States Patent Office.

AUGUSTUS P. SHUTE AND JOHN F. JACKSON, OF CHARLESTOWN, MASSACHUSETTS.

Letters Patent No. 70,127, dated October 22, 1867.

IMPROVED EXTENSION-TABLE SLIDE.

The Schedule referred to in these Letters Patent and making part of the same.

TO ALL WHOM IT MAY CONCERN:

Be it known that we, AUGUSTUS P. SHUTE and JOHN F. JACKSON, both of Charlestown, in the county of Middlesex, and State of Massachusetts, have invented an improved Extension-Table Slide; and we do hereby declare that the following is a full and exact description thereof, reference being had to the accompanying drawings, and to the letters of reference marked thereon.

The nature of our invention consists in providing the sliding bars of an extension-table with narrow metallic strips, running parallel to each other and longitudinally with the bars, but inclined to each other in section, working in corresponding grooves, thus making a neat, strong, and cheap sliding connection for the bars.

To enable others skilled in the art to make and use our invention, we will proceed to describe its construction and use. In the drawings—

Figure 1 is a perspective view, showing a set of these bars as they appear when drawn out.

Figure 2 is an elevation and part section, the elevation being represented as though cut off on the line Y, fig. 3.

Figure 3 is an end elevation of our slide.

We construct our slide as follows: We make, of any suitable wood, a number of bars A B C, and with a circular saw, or with any other convenient tool, make the grooves E E'' parallel to each other in a longitudinal direction, as shown in figs. 1 and 2, but inclined to each other in cross-section, as shown in fig. 3. The depth and width of these grooves may be varied to suit the requirements of the case. A short thin piece of metal, D''', fig. 2, is inserted into the grooves at one end of each bar, and made fast by means of screws or nails, so that if two of the bars are put together, as shown by A and B, fig. 3, two of these inclined metallic pieces D D' would be attached to B, and would slide in the grooves E E' of A. Each bar being provided with sets of these metallic pieces D D', &c., it will be seen that the bars slide upon each other until the metallic pieces strike each other, as shown by D'' D''', fig. 2. To prevent the bars from being slipped backwards by each other, pins K K' are inserted into the pieces A and B.

The number of bars would vary to suit the requirements of the table, a long table requiring many and a short table but few.

The advantages that we claim for our invention are extreme simplicity, cheapness, and durability.

Having thus described our invention, we will proceed to set forth our claim.

What we claim as our invention, and desire to secure by Letters Patent, is—

The combination, as well as the arrangement, of the metallic slips D D' D'' with the grooves E E' and the bars A B C, made substantially as described and for the purpose set forth.

AUGUSTUS P. SHUTE,
JOHN F. JACKSON.
